E. KAUFFELD

SAFETY STOP FOR LOCOMOTIVES

Filed Sept. 30, 1926

UNITED STATES PATENT OFFICE.

ELIAS KAUFFEELD, OF PITTSBURGH, PENNSYLVANIA.

SAFETY STOP FOR LOCOMOTIVES.

Application filed September 30, 1926. Serial No. 138,638.

My invention relates to safety stops for locomotives and more particularly to stops for use with what is known as "straight air" systems of brake control.

5 My invention has for its object the provision of means for stopping locomotives and trains in case danger signals are not heeded. It is a particular object of this invention to make the stopping of the locomotive and the cars attached thereto entirely 10 automatic in case a danger signal has been passed. I provide means independent of the engineer's throttle lever for cutting off the steam from the steam cylinders and I 15 provide means whereby the engineer can not, in case of the operation of my stop, readily release the train pipe pressure and thereby release the brakes. I provide means also to prevent the setting of the brakes so 20 suddenly as to injure persons on the train. Another object is to provide means by the side of the track whereby a flagman or other person may set the stop operating mechanism when the signal operator in the tower 25 neglects to set the stop. Another object is to provide a novel lock which keeps the brakes set until the engineer leaves his cab and manually releases the lock. Other objects appear hereinafter.

30 Referring to the accompanying drawing, Fig. 1 represents my invention diagrammatically with parts broken away and omitted; Fig. 2, a plan view of that part of my invention which is connected with the track; 35 Fig. 3, a section of Fig. 2 on the line III—III; and Fig. 4, a section of Fig. 1 on the line IV—IV.

On the drawing, 1 designates a metal tripping device having the base 2 and the 40 opposite upstanding flanges or sides 3. The device 1 rests on the track ties 4 to which the base 2 is secured by the nails 5. The opposite end of the sides 3 are provided near their upper edges with pivots 6 on 45 which the outer ends of two metal trip- plates 7 are pivoted, the inner ends of the plates being pivotally connected together by the cross-pivot 8. The plates 7 have depending flanges 9 which overlap the outer faces of the sides 3 and have horizontal 50 elongated holes 10 to receive the pivots 6.

In the sides 3 are journaled two shafts 11 and 12 having between the said sides the cranks 13 and 14. The crank 13 when raised 55 vertically above the shaft 11 engages a pendent metal strip 15 on the left plate 7

and lifts the plates 7, the strip 15 having the stop 16 to stop the crank in a vertical position. The shaft 11 has the pendent arm 17 operable by one end of the horizontal 60 lever 18 pivoted between its ends on the pin 19 in the plate 20 secured to two of the ties 4. The remaining end of the lever 18 is pivoted to the bar 21 operable from a nearby signal tower, not shown.

65 The shaft 12 is manually operated by the handle 22 which may be locked in the fork 23 by the padlock 24 when the crank 14 is down as shown in the drawing. When the handle is thrown 180° from the position 70 shown, it lies in the fork 24 where it may be locked by the padlock. Upon turning the handle from the fork 23 to the fork 24, the crank engages the pendent strip 25 on the right plate 7 and lifts the plates 7 to the 75 position shown. The strip 25 has the stop 26 which stops the crank 14 in a vertical position above the shaft 12.

27 is the engineer's air-valve which he 80 manually controls in the usual manner for setting and releasing the air-controlled brakes. 28 is the main air tank supplied with air from a pump, not shown, connected to the pipe 29. Air in the tank may flow through the pipe 30 to the T-fitting 31 from 85 which it may flow through the pipe 32 to the valve 27 and through the pipe 33, the valve 34, the pipe 35, the check-valve 36, and the pipe 37 to one branch of the Y-fitting 38. The check valve 36 may be any well 90 known type of device for automatically delaying the time required to build up the air pressure so that the brakes will not be set 95 too suddenly and cause damage to persons and property. Air may flow between the valve 27 and a second branch of the Y-fitting by way of the pipe 39, the valve 40, and the pipe 41. The remaining branch of the Y-fitting 38 is provided with the train 100 pipe 42 which is connected to the usual brake-controlling mechanism, on the locomotive and each car of the train connected to the locomotive. 43 is the usual exhaust outlet for the valve 27 whereby air is drained through the valve 27 and from the 105 train pipe 42 in order to release the brakes and hold them released.

44 is the steam supply pipe containing the 110 throttle valve 45 and the valve 46. The valve 45 is controlled by the throttle lever 47 in any desired manner, as by the rod 48.

49 is a lever pivoted between its ends to a

convenient support on the locomotive and 57 and which upon movement of the lever 49 having one end between the valves 34 and 46 and the other end below the valve 40. The valves 34 and 46 are controlled by stems 50 and 51 pivoted to the lever 49, and the valve 40 is controlled by the stem 52 pivoted to the lever 49. The valves are so constructed and controlled that, when the valve 34 is closed, the valves 40 and 46 are open, and, when the valve 34 is open, the valves 40 and 46 are closed.

53 is a lever pivoted between its ends to a convenient support on the locomotive. One end is pivotally connected by the link 54 to that end of the lever 49 which carries the stem 52. The other end of the lever 53 carries the roller 55. The parts are so arranged and proportioned that, when the plates 7 are down, or horizontal, the roller passes directly over them without being operatively engaged by them, and when the plates are elevated, as shown, the roller engages the plates and causes the levers 49 and 53 to be rocked so as to open the normally closed valve 34 and close the normally open valves 40 and 46. The valve 34 is normally closed so that air may not normally pass directly to the train pipe 42. The valve 40 is provided to prevent air from the tank 28 passing from the Y-fitting to the exhaust outlet 43 whenever the emergency valve 34 is opened. Normally the steam valve 46 is open so that the engineer may control the supply of steam to the locomotive cylinder. When the train is running normally with the brakes released and the roller 55 in its lowest position, which requires the valve 34 to be closed and the valves 40 and 46 to be open, the engineer has full control of the steam and air precisely as he would have if my improvement were not present.

When the stop plates 7 have been elevated indicating "danger" and requiring that the locomotive shall not pass the same, and the engineer disregards the same, the roller 55 by engagement with the stop plates 7 causes (1) the steam valve to be closed without any operation of the throttle lever 47, the steam being therefore cut off without any possibility of the engineer's preventing it, because the valve 46 is controlled by means entirely independent of the throttle lever 47; (2) the air is admitted to the train pipe 42 through the valve 34 which by-passes the engineer's air-valve 27 and is wholly independent of the same; (3) the air admitted thus to the train pipe is prevented by the closure of the valve 40 from escaping through the exhaust outlet 43 and is therefore applied to the brakes without the possibility of prevention by the engineer, his valve 27 being entirely inoperative; and (4) the lever 49 is locked in the position shown in Fig. 1 by the spring-actuated pin 56 which normally has its inner end in the shallow upper portion of the slot

57 and which upon movement of the lever 49 to the position shown is pushed by the spring 58 into the hole 59 in the lever at the lower end of the slot 57. Preferably the locking device just described is located at a point on the locomotive which requires the engineer to leave his cab in order to pull the pin out of the hole 59 and reset the stop mechanism to its normal state.

In case a train should come to rest just after passing a danger signal, the flagman going back could by operating the lever 22 elevate the plates 7, if he finds them down, or in case the train is to back to its proper place behind the signal, he can lower the plates, if they are still up, so that my emergency mechanism can not be operated. The lever 22 can be used whenever the towerman has not properly set the signals and the plates 7.

I claim—

1. For a train equipped with a straight air system of brake control, a train pipe, a source of compressed air therefor, an engineer's valve in the train pipe, a by-pass around the said valve, a normally closed valve in the by-pass, and means operable by a track obstruction for automatically preventing the flow of air through the engineer's valve and automatically opening the valve in the by-pass.

2. For a steam-operated train equipped with a straight air system of brake control, a steam pipe, an engineer's valve therein, a train pipe, an engineer's valve therein, a source of compressed air for the train pipe, a by-pass around the second valve, a normally closed valve in the by-pass, and means operable by a track obstruction for preventing the flow of steam and air through the said pipes and for automatically opening the valve in the by-pass.

3. For a train equipped with a straight air system of brake control, a train pipe, an engineer's valve therein, a normally open valve in the train pipe, a source of compressed air for the train pipe, a by-pass around the said two valves, a normally closed valve in the by-pass, and means operable by a track obstruction for automatically closing the second valve and opening the valve in the by-pass.

4. For a train equipped with a straight air system of brake control, a train pipe, a source of compressed air therefor, an engineer's valve in the train pipe, a by-pass around the said valve, a normally closed valve in the by-pass, means operable by a track obstruction for automatically preventing the flow of air through the engineer's valve and automatically opening the valve in the by-pass, and means in the by-pass for automatically delaying the time required to build up the air pressure in the train pipe beyond the last said means.

5. For a train equipped with a straight air system of brake control, a train pipe, a source of compressed air therefor, an engineer's valve in the train pipe, a by-pass around the said valve, a normally closed valve in the by-pass, means operable by a track obstruction for automatically preventing the flow of air through the engineer's valve and automatically opening the valve in the by-pass, and a releasable means distant from the engineer's normal position, for automatically locking the preventing means and the valve in the by-pass, in the positions to which they are moved by the track obstruction.
10. For a train equipped with a straight air system of brake control, a train pipe, an engineer's valve therein, a normally open valve in the train pipe, a source of compressed air for the train pipe, a by-pass around the said two valves, a normally closed valve in the by-pass, means operable by a track obstruction for automatically closing the second valve and opening the valve in the by-pass, and releasable means for locking the second valve and the valve in the by-pass in the positions to which they are moved by the track obstruction.
15. For a train equipped with a straight air system of brake control, a train pipe, an engineer's valve therein, a normally open valve in the train pipe, a source of compressed air for the train pipe, a by-pass around the said two valves, a normally closed valve in the by-pass, means operable by a track obstruction for automatically delaying the time required to build up the air pressure in the train pipe beyond the last said means.
20. For a train equipped with a straight air system of brake control, a train pipe, an engineer's valve therein, a normally open valve in the train pipe, a source of compressed air for the train pipe, a by-pass around the said two valves, a normally closed valve in the by-pass, means operable by a

track obstruction for automatically closing the second valve and opening the valve in the by-pass, and releasable means for locking the second valve and the valve in the by-pass in the positions to which they are moved by the track obstruction.

25. For a train equipped with a straight air system of brake control, a train pipe, an engineer's valve therein, a normally open valve in the train pipe, a source of compressed air for the train pipe, a by-pass around the said two valves, a normally closed valve in the by-pass, means operable by a track obstruction for automatically closing the second valve and opening the valve in the by-pass, and releasable means for locking the second valve and the valve in the by-pass in the positions to which they are moved by the track obstruction.

30. For a train equipped with a straight air system of brake control, a train pipe, an engineer's valve therein, a normally open valve in the train pipe, a source of compressed air for the train pipe, a by-pass around the said two valves, a normally closed valve in the by-pass, means operable by a track obstruction for automatically closing the second valve and opening the valve in the by-pass, and releasable means for locking the second valve and the valve in the by-pass in the positions to which they are moved by the track obstruction.

35. For a train equipped with a straight air system of brake control, a train pipe, an engineer's valve therein, a normally open valve in the train pipe, a source of compressed air for the train pipe, a by-pass around the said two valves, a normally closed valve in the by-pass, means operable by a track obstruction for automatically closing the second valve and opening the valve in the by-pass, and releasable means for locking the second valve and the valve in the by-pass in the positions to which they are moved by the track obstruction.

40. For a train equipped with a straight air system of brake control, a train pipe, an engineer's valve therein, a normally open valve in the train pipe, a source of compressed air for the train pipe, a by-pass around the said two valves, a normally closed valve in the by-pass, means operable by a track obstruction for automatically closing the second valve and opening the valve in the by-pass, and releasable means for locking the second valve and the valve in the by-pass in the positions to which they are moved by the track obstruction.

In testimony whereof I hereunto affix my signature.

ELIAS KAUFFELD.
